UNITED STATES PATENT OFFICE

2,411,449

ROTARY TYPE CAN OPENER

Robert E. McLean, Fort Benning, Ga.

Application December 3, 1943, Serial No. 512,794

5 Claims. (Cl. 30—9)

1

This invention relates generally to the class of cutlery and more particularly relates to implements designed for the opening of sealed metallic receptacles, such as tin cans and the like, the present application being based upon and setting forth certain novel improvements over the structures disclosed in my prior Patents No. 2,287,442 of June 23, 1942, No. 2,294,507 of September 1, 1942, and 2,314,506 of March 23, 1943.

An object of the present invention is to provide in a can opener of the type employing a rotary can driving wheel as herein disclosed, a novel and improved escapement mechanism between an operating crank and a thrust element actuating arm wherein such escapement is effected more quickly and smoothly and with the expenditure of less force or effort than is possible with the escapement mechanisms disclosed in the prior patents referred to.

The rotary can openers of the stated prior patents and of the present application employ in association with a cutter and a can rim engaging and driving wheel which is rotated by means of a suitable type of crank, a thrust means for effecting relative movement between the cutter and the driving wheel, with mechanism for cooperatively coupling the crank means with the means for effecting the stated relative movement between the wheel and cutter, when the crank is turned in a desired direction, so as to effect shifting of the can towards the cutter to bring about penetration of the can head by the cutter and the cutting away of the head or the shifting of the can away from the cutter after such head has been cut away.

The operative coupling established between the crank means and the said movement effecting means is intermittently operated upon turning of the crank and in the present case certain embodiments of an improved and novel escapement mechanism are shown whereby the desired coupling of the handle with the means for producing the stated relative movement between the wheel and cutter, is accomplished until the limit of such movement is reached, because of the improved construction, the coupling will be automatically released or disengaged with a minimum of effort to permit continued free movement of the crank for the operation of the driving wheel.

Other objects and advantages of the invention will become apparent as the description of the same proceeds and the invention will be best understood from a consideration of the following detailed description taken in connection with

2

the accompanying drawing, it being understood, however, that the invention is not to be considered as limited by the specific illustration or description but that minor changes and modifications may be made therein so long as such changes and modifications are within the scope of the appended claims.

In the drawing:

Fig. 1 is a view in side elevation of the right-hand side of an embodiment of the escapement mechanism which is adapted to be used in association with any one of the several forms of rotary drive wheel can opener structures in my prior patents hereinbefore referred to.

Fig. 2 is a view in front elevation of the mechanism of Fig. 1.

Fig. 3 is a view in elevation of the right-hand side of another embodiment of the escapement, parts being broken away.

Fig. 4 is a view in front elevation of the mechanism shown in Figure 3.

Fig. 5 is a view in elevation of the right-hand side of a further embodiment of the escapement, portions being broken away.

Fig. 6 is a view in front elevation of the embodiment shown in Fig. 5.

Figure 7 is a view in front elevation of one form of my rotary drive wheel type can opener, showing the application of the escapement shown in Figures 1 and 2.

Referring now more particularly to the drawing, Figures 1 and 2 illustrate one embodiment of the improved escapement which is designed to be used in association with any of the several designs of can openers shown in my prior patents previously referred to.

It is contemplated to use any of the various embodiments of the escapement with any of the different forms of top construction illustrated in my prior Patents 2,287,442; 2,294,507 and 2,314,506.

In Figures 1 and 7 the reference numeral 1c indicates an elongated body plate which is secured to a supporting member 2, which is designed to be attached to a suitable wall bracket, not shown, so as to dispose the body plate in upright position when set up for use.

A type of wall bracket designed particularly for use in association with my several forms of can opener, is illustrated in my pending application Serial No. 484,626.

At its upper end the body plate 1c is shaped to provide the laterally offset shoulder 3 which extends across the left-hand side of the plate and above this shoulder the body plate is shaped

to provide a head 4 which comprises the inclined side wall 5, the laterally extending top 6 and the depending spring arm 7, which is in spaced opposed relation to the wall 5. The wall 5 and the arm 7 have aligned bearing openings 8 and 9 through which is extended a bearing sleeve 10 which is held against rotation. Extending through this sleeve is a cutter wheel shaft 12 which carries the cutting wheel 14 and between this cutting wheel and the adjacent wall 5 there is supported, upon the shaft 12, the idler wheel 13, against which the edge of the rim of a can C bears when being turned during the operation of cutting out the head of the can.

The body plate has formed therein just below the shoulder 3, the elongated longitudinally extending elliptical slot 15 in which is fitted the circular collar 16. This collar has turning movement in the slot and also longitudinal movement therein and it carries, and has extending therethrough, the coupling sleeve 17 which, upon the side of the plate nearest the cutting wheel, passes through and is secured to a thrust element, in the form of an eccentric wheel 18. The periphery of this eccentric wheel contacts the overlying shoulder 3.

At its other end the coupling sleeve 17 is secured in the laterally offset upper end portion 19 of an escapement carrying arm 20c, herein-after more specifically described.

Disposed across the side of the body plate 1c directly beneath the eccentric wheel 18 and having contact with the lower peripheral portion thereof, is a yieldable arm 21 which forms an integral continuation of a relatively wide lower or underlying portion 22 which is in the form of a plate secured between the body 1c and the supporting member 2.

The coupling sleeve 17, which joins together the plate of the escapement unit, the sliding collar 16 and the eccentric wheel 18 forms a bearing for a shaft 23. This shaft extends at one end beyond the eccentric wheel and carries a milled edge driving wheel 24 which is disposed directly below the idler wheel 13 and, when in raised or operative position, has its top edge in overlapping relation with the lowermost portion of the cutting edge of the wheel 14, upon the inner side of such wheel, whereby to effect the turning of the can C, through the engagement of the top flange or rim of the can between the wheel 24 and the idler 13. The head of the can which is punctured by the edge of the cutting wheel, may then be cut out by rotating the can through the rotation of the driving wheel 24, with respect to the cutter wheel.

The shaft 23 extends a substantial distance to the right of the body 1c, where it has secured to its right hand end, the operating crank handle 25, the upper end of which handle is maintained in the desired spaced relation with respect to the upper end portion of the escapement unit plate 20c, by a spacing sleeve 26 which may extend through the coupling sleeve 17.

As previously stated the upper end portion of the escapement arm 20c is offset, thereby providing the shoulder 27 which is perpendicular to the length of the arm and the body of the arm below this shoulder is widened to have the rearwardly extending portion 66 which is bordered by the inwardly extending flange 67 which passes part way across the lower edge of the arm forming the forwardly facing stop edge 68. In this escapement the arm plate carries an inwardly extending keeper stud 69 and below this

stud and slightly forwardly therefrom, when the arm 20c is hanging vertically as shown, is a trip stud 70 which is carried by the body 1c.

Adjacent the rear of the rearwardly extending portion 66 of the arm 20c is fixed the inwardly extending pivot 71 upon which is pivotally mounted the trigger link 72 which, when the arm 20c is vertical as shown, assumes a substantially horizontal position.

The forward end of the trigger link 72 carries a pivot 73, to one end of which is secured an end of the upwardly extending latch finger 74 the upper end of which finger has its forward edge notched or cut out as indicated at 75 to receive a corner of the keeper stud 69 which is of rectangular cross section as shown.

Integral with the forward end of the link 72 is the depending trigger 76 which extends below the lower end edge of the arm 20c. The downward swinging of the link 72 and consequently the rearward swing of the trigger is limited by the stop 68 of the arm flange. The latch oscillates upon the pivot 73 and it will be readily seen that upon clockwise rotation of the crank handle to bring the trigger finger against the rear edge of the trigger, the application of forward pressure to the escapement mechanism carrying arm 20c, when the arm is in the hanging position shown, will force the latch against the immovable stud 70 and thus cause the upper end of the latch to slip out of contact with the keeper stud 69 thereby allowing the trigger 76 to swing in a clock-wise direction a sufficient distance to escape from the trigger finger carried by the handle. Upon reverse movement of the handle the trigger finger will engage the forward edge of the trigger 76 and swing the arm 20c in a counter-clockwise direction so as to release a can held between the driving wheel and the cutter wheel and at the same time due to the downward swinging of the trigger link 72 the latch finger 74 will move to a position where it may again receive the adjacent corner of the keeper stud 69 in the notch 75.

Figures 3 to 6 inclusive illustrate the embodiments of the escapement wherein the latch element is pivotally attached to the arm and has a detachable coupling with the trigger rather than being pivotally connected to the trigger as illustrated in Figure 1. In Figures 3 and 4 the body plate is designated 1g and the arm is designated 20d. Upon the body 1g adjacent the forward edge is the stop pin 146. The arm 20d carries a pivot pin 147 upon which is pivotally mounted, between the arm and the body plate 1g, the hanging latch finger 148 which extends below the stop 146 as shown. The lower end of this arm is notched at its forward edge as indicated at 149 and the arm is normally urged to swing forwardly by a suitable spring such as that indicated at 150, the spring being mounted upon the arm 20d.

At the lower end of the arm 20d and rearwardly from the latch finger 148 is the pivot pin 151 upon which is pivotally mounted an end of a forwardly extending link 152 which is inwardly offset and provided at its forward end with the transverse terminal lip 153 the upper edge of which is designed for engagement in the notch 149 at the lower end of the latch finger. This link 152 carries, adjacent its forward end, the depending trigger 154, which extends below the lower edge of the arm 20d as shown to be engaged by the trigger finger carried by the handle of the cutter.

The stop pin 155 lies upon the inner side of the arm 20d above the link 152 and limits the upward swinging of this link and the trigger 154.

In the embodiment shown in Figures 5 and 6 the body plate is designated 1h and the arm carrying the escapement mechanism is designated 20e. The trip pin for the latch finger is indicated at 146a, being supported upon the body as in the preceding construction while the pivot for the latch finger is indicated as 147a and is supported upon the arm 20e and suspends the latch finger 148a upon the inner side of the arm as shown.

The forward edge of the arm 20e at the lower end carries the inwardly turned stop finger 157a. A corresponding stop finger 157 is integral with and extends inwardly from the lower edge of the arm 20d of the structure shown in Figure 4.

The trigger link, trigger and the latch finger engaged part thereof are, in this construction, formed of a single length of material, the link portion being designated 152a and being turned at one end to form an eye 158 through which the pivot pin 151a, carried by the lower end of the arm, extends. The trigger is designated 154a and merges with the upwardly extending portion 159 which in turn merges with the horizontal forwardly projecting ear or tip 160 which engages across the stop 157a to limit the downward swinging movement of this unit. The corner formed between the parts 159 and 160 engages in the notch 148a at the lower end of the trigger finger. The spring element 150a engages the latch finger and normally urges it forwardly so that a secure connection will be maintained between the finger and the trigger.

It is believed that the operation of the escapements shown in Figures 3 to 6 inclusive will be readily apparent in the light of the description given in connection with the preceding embodiment of the escapement.

I claim:

1. A rotary type can opener comprising a body, a cutter carried by the body, a rotary can driving wheel supported on the body for movement relative to the cutter, a crank for turning the wheel, a thrust means for effecting relative movement between the wheel and cutter, an arm connected with said thrust means for oscillatory movement around the axis of turning for the crank, a trigger link carried by and extending substantially transversely of the outer end of the arm, a trigger carried by the link and extending radially beyond the outer end of the arm, a latch finger pivotally attached at one end to said link and extending substantially longitudinally of the arm, a keeper member carried by the arm and adapted for operative connection with the free end of said latch finger for opposing oscillation of the trigger link, a trip member carried by the body in the path of movement of said latch finger for effecting shifting of the latch finger from connection with the keeper, and means carried by the crank for engagement with the trigger upon turning of the crank whereby rotation of the arm and crank as a unit is effected, said trigger being released from the crank carried means upon disengagement of the latch finger from said keeper.

2. In a rotary type can opener including a cutter, a rotary can driving wheel movable relative to the cutter, a crank for turning the wheel and a thrust means for effecting relative movement between the wheel and the cutter; an oscillatable arm operatively coupled with said

thrust means to actuate the thrust means, a trigger comprising a relatively long body disposed adjacent to the arm to extend transversely thereof and having an end pivoted to the arm at one side of the longitudinal center of the arm, the trigger oscillating vertically on the arm, means carried by the crank for connection with the trigger for effecting movement of the arm and crank together as a unit through a predetermined extent in a circular path, a relatively long finger extending longitudinally of the arm upon the opposite side of said center from the trigger pivot and movably supported for connection with the trigger to maintain the trigger in a position transversely of the arm whereby to maintain connection between the trigger and the crank, and means acting after a predetermined degree of unitary movement of the trigger carrying arm and crank, to effect disconnection of the trigger from the crank carrying means, permitting continued movement of the crank only.

3. In a rotary type can opener including a cutter, a rotary can driving wheel movable relative to the cutter, a crank for turning the wheel and a thrust means for effecting relative movement between the wheel and the cutter; an oscillatable arm operatively coupled with said thrust means to actuate the thrust means, a relatively short trigger member having a greater length than width, pivotally attached at one end to the arm and extending transversely thereof, said trigger having a portion extended below the arm, means carried by the crank for connection with said extended portion for effecting movement of the arm and crank together as a unit through a predetermined extent in a circular path, a relatively long shiftable member pivotally attached to the other end of the trigger and extending lengthwise of the arm in line with but away from said trigger portion, an element carried by the arm and adapted to be engaged by the other end of the shiftable member for holding the shiftable member against movement longitudinally of the arm and securing the trigger member against oscillation, and a fixed means disposed in the path of movement of the shiftable member to be engaged by the said shiftable member after a predetermined degree of unitary movement of the trigger carrying arm and crank, to effect the shifting of the shiftable member and release of the trigger member from the crank to permit continued movement of the crank only.

4. In a rotary type can opener including a cutter, a rotary can driving wheel movable relative to the cutter, a crank for turning the wheel and a thrust means for effecting relative movement between the wheel and the cutter; an oscillatable arm operatively coupled with said thrust means to actuate the thrust means, a shiftable trigger, said trigger having a length extending transversely of the arm and pivotally attached at one end to the arm, the trigger at the other end being formed to provide a lateral shoulder, a relatively long member pivotally attached at one end to the arm above said shoulder to lie lengthwise of the arm in line with said shoulder, said member at its free end engaging over said shoulder to maintain the trigger against vertical oscillation, and a fixed member lying in the path of movement of said long member to engage and shift the latter out of connection with said shoulder, the trigger having a downwardly extending portion, means carried by the crank for connection with said downwardly extending portion for effecting movement of the arm and the crank

7 together as a unit through a predetermined extent in a circular path, said fixed member acting to shift the said long member after a predetermined degree of unitary movement of the trigger carrying arm and crank to effect disconnection of the trigger from the crank carrying means, permitting continued movement of the crank only.

5 5. A rotary type can opener as set forth in claim 4, with a flange element carried by the arm and engaged by the shoulder forming means of the trigger to limit the downward swinging movement of the trigger member.

ROBERT E. McLEAN.
